UNITED STATES PATENT OFFICE.

ANDREW J. REAMS, OF CHICAGO, ILLINOIS, ASSIGNOR TO THE PROGRAM CLOCK COMPANY, OF ILLINOIS.

ELECTRICAL PROGRAM-CLOCK.

SPECIFICATION forming part of Letters Patent No. 563,883, dated July 14, 1896.

Application filed November 20, 1895. Serial No. 569,547. (No model.)

To all whom it may concern:

Be it known that I, ANDREW J. REAMS, a citizen of the United States, residing at Chicago, in the county of Cook and State of Illinois, have invented a certain new and useful Improvement in Electrical Program-Clocks, (Case No. 1,) of which the following is a full, clear, concise, and exact description, reference being had to the accompanying drawings, forming a part of this specification.

My invention relates to an electrical program-clock, its object being to provide an improved construction of clock mechanism and a circuit-controlling device whereby a signal may be sounded at any predetermined time.

Upon the face of the clock I provide a series of contacts adapted to be placed at will in position to be engaged by a contact carried upon the hour-hand, the contacts being preferably in the form of a ring, upon which contact-fingers are rotatably mounted, whereby they may be moved into a position with their ends projecting into the path of the traveling contact, or they may be rotated into a position to rest out of the path of the traveling contact. The contacts may thus be arranged to sound a signal at any predetermined time. The hour-hand, instead of traveling continuously, as has been the usual practice, is adapted to be moved at intervals, that is, step by step, the driving mechanism of the hour-hand being normally locked, but released at intervals, preferably every five minutes, to move the hour-hand forward through a space corresponding to five minutes. By this arrangement the closing of the circuit between the contact carried upon the hour-hand and the contact provided upon the face of the clock may be effected at the precise instant of time desired. A circuit-controller is operated by the mechanism which moves the hour-hand, so that when the hour-hand is rotated the continuity of the circuit is completed through the normally open circuit-controller for an interval of time, the interval during which the bell or other signal device is sounded being thus always uniform.

I will describe my invention more in particular by reference to the accompanying drawings, in which—

Figure 1 is a view of the face of a program-

clock embodying my invention, the circuit arrangements being indicated diagrammatically. Fig. 2 is a detailed view showing the contact-fingers mounted upon the face of the 55 clock and the contact carried upon the hour-hand. Fig. 3 is a view in elevation of the clock mechanism. Fig. 4 is a view of the mechanism for rotating the hour-hand as seen from the opposite side to that of Fig. 3. 60

Like letters refer to like parts in the several figures.

Upon the face of the clock is mounted a metallic ring *a*, upon which are rotatably mounted contact-fingers *a'*, the fingers being preferably arranged at intervals corresponding to five minutes. When rotated toward the center of the ring, the ends of the contact-fingers rest in the path of the contact *b'*, carried upon the hour-hand *b*, and when rotated in the opposite direction the contact-fingers lie out of the path of the contact *b'*. By rotating the desired contact-fingers into the path of the traveling contact an alarm may be sounded at any predetermined time. 75

The ring *a* is connected with one side of a battery or other source of electricity *c*, circuit then extending through the bell or signal device *c'*, thence to the contact-spring *c*², to the rotating disk *c*³, with the periphery of which 80 the spring *c*² is adapted to make contact when the disk is rotated, the spring *c*² normally resting out of engagement with the disk. The disk *c*³ is electrically connected with the clock mechanism with which the hour-hand *b* is in 85 electrical connection, the circuit thus extending through the hour-hand to the contact *b'*, carried upon the end thereof, and thence to the particular contact-finger *a'*, with which the contact *b'* may engage. 90

The contact *b'*, carried upon the hour-hand, comes in contact with one of the contact-fingers *a'*, and when the mechanism driving the hour-hand is released the disk *c*³ is rotated, thus completing circuit from the battery *c* 95 through the bell *c'*, spring *c*², disk *c*³, hour-hand *b*, contact *b'*, contact-finger *a'*, to the opposite side of the battery. When disk *c*³ has made a half-rotation, the contact between the spring *c*² and the disk *c*³ is broken and the contact *b'* is moved out of engagement with the contact-finger *a'*. 100

To effect the step-by-step movement of the hour-hand b , the hour-hand is mounted loosely upon the shaft d , which carries the minute-hand, a ratchet-wheel b^2 being mounted to move with the hour-hand. A pawl b^3 is provided for rotating the ratchet-wheel b^2 and is carried upon a pivoted lever b^4 , the end of which is adapted to be engaged by the teeth of a wheel e , the wheel e being driven by the spring f through intermediate gearing. The wheel e is provided with sixteen teeth and is rotated a tooth at a time at the end of each interval of five minutes, the end of the lever b^4 thus riding upon the tooth and causing the pawl b^3 to slide over the periphery of the ratchet-wheel b^2 . When the end of the lever b^4 passes over the point of the tooth, a spring b^5 depresses the lever, thus moving the pawl b^3 to rotate the ratchet-wheel b^2 and thus advance the hour-hand b through a space corresponding to five minutes. Upon the shaft e' , carrying the wheel e , is mounted a toothed wheel e^2 , meshing with a pinion e^3 , carried upon a shaft e^4 . The disk c^3 of the circuit-controller is mounted upon the shaft e^4 and is provided in its periphery with diametrically-situated notches c^4 , in which the end of the contact-spring c^2 is adapted to normally rest, circuit being thus opened between the contact-spring and the disk. The disk c^3 is adapted to rotate through a half-revolution while the wheel e is rotating through the distance of one tooth. As the disk c^3 rotates the end of the spring c^2 rides upon the periphery thereof, thus completing the circuit, the end of the spring falling into the opposite notch c^4 upon the completion of a half-rotation of the disk. Upon the shaft e^4 is mounted a disk g , provided at opposite points in its periphery with notches g^4 , in which the end of a rod or arm g^2 is adapted to rest. When the train begins to move, the arm g^2 is moved out of the notch g^4 and rides upon the periphery of the disk g until the disk has completed a half-revolution, when it falls into the opposite notch g^4 . The arm g^2 is mounted upon the rocking shaft g^3 , which carries an arm g^4 , engaged by an arm h' , carried upon the rocking shaft h . An operating arm or rod h^2 is mounted upon the rocking shaft h and is engaged at its upturned end by pins h^3 , mounted upon a disk or wheel h , carried upon the shaft d , upon which is mounted the minute-hand. The pins h^3 are twelve in number, and, as the shaft d makes one revolution each hour, the distance between the pins h^3 corresponds to five minutes. As the wheel h rotates one of the pins h^3 engages the under side of the upturned end of arm h^2 , thus rocking the shaft h , and, through the engagement of arm h' with arm g^4 , the shaft g^3 is likewise rocked, thus raising the end of arm g^2 out of the notch g^4 . Upon the rocking shaft g^3 is also mounted an arm g^5 , which normally engages a pin or stop l , carried upon the wheel l' , which meshes with a pinion l^2 , mounted upon a shaft carrying the regulating-fan l^3 .

A pinion is mounted upon the same shaft with the wheel l' and meshes with the wheel l^2 , carried upon the shaft e^4 . When the arm h^3 is engaged by one of the pins h^3 to rock the shafts h and g^3 , the arm g^5 is raised out of engagement with the stop l , and the arm g^2 is moved out of engagement with the notch g^4 , thus permitting the train to rotate through a short distance until the stop l engages the arm h^4 , carried upon the rocking shaft h . The movement of the train is thus checked until the pin h^3 has completely passed the upturned end of the rod h^2 and permits the rod to move inward beneath the pin that has just passed. This movement of the rod h^2 carries the arm h^4 out of the path of the stop l and permits the train to rotate. The end of arm g^2 now rides upon the periphery of the disk g , thus maintaining the arm g^2 out of the path of the stop l . When the disk g has completed a half-revolution, the arm g^2 falls into the opposite notch g^4 , thus moving the end of the arm g^2 into the path of the stop l and checking the movement of the train. The movement of the train is sufficient to rotate the wheel e through the distance of one tooth, thus operating the pawl b^3 and moving the hour-hand through the distance corresponding to five minutes. During the movement of the train the contact-spring c^2 rides upon the periphery of the disk c^3 , thus completing circuit through the circuit-controlling device. Supposing the hour-hand b to be resting against one of the contact-fingers a' when the train is started in motion, circuit will be closed through the bell so long as the contact-spring c^2 engages the disk c^3 . At the completion of the movement of the train the hour-hand b is moved forward by the pawl b^3 and the circuit is opened between the spring c^2 and disk c^3 .

Having described my invention, what I claim as new, and desire to secure by Letters Patent, is—

1. In a program-clock, the combination with the time-keeping clock-train, of an hour-hand carrying the traveling contact, a second driving-train the intermittent movement of which is controlled by the clock-train, a ratchet-wheel mounted to rotate with the hour-hand, a pawl for rotating said ratchet-wheel, a toothed wheel for operating said pawl connected in the driving-train of the hour-hand and thereby periodically rotated the distance of a single tooth to advance the hour-hand of the clock step by step, substantially as described.

2. The combination with the time-keeping train of a clock, of a controlling-wheel actuated thereby rotating with the minute-hand, a second driving-train and spring actuating the hour-hand of the clock, an hour-hand carrying the traveling contact, and a lever for controlling the driving-train of the hour-hand controlled by the rotation of said controlling-wheel, substantially as described.

3. In a program-clock, the combination with

- a time-keeping train actuating the minute-hand, of a separate driving-train and spring actuating the hour-hand thereof, contacts adjustably disposed upon the face of the clock, 5 an hour-hand and a traveling contact mounted thereon adapted to successively engage the adjusted contacts on the face of the clock as the said hour-hand is rotated, substantially as described.
- 10 4. The combination with the driving-train of a clock actuating the minute-hand, of an hour-hand loosely mounted upon the shaft of the minute-hand, a second driving-train and spring actuating the hour-hand, a traveling 15 contact carried upon the hour-hand, contacts provided upon the clock-face adapted to be adjustably disposed in position to be engaged by the traveling contact, a stop normally checking the said second driving-train adapt- 20 ed to be intermittently actuated by the clock-train to release the said driving-train and permit the advance of the hour-hand and traveling contact step by step to successively engage the adjusted contacts upon the clock- 25 face, substantially as described.
5. In a program-clock, the combination with the clock-train, of a separate driving-train and spring for the hour-hand, the movement of which is controlled by the clock-train, adapted 30 to periodically advance the hour-hand step by step, a plurality of contacts upon the clock-face, each of which may be adjusted to be engaged by the traveling contact, a traveling contact carried upon the hour-hand and 35 adapted to engage the said adjusted contacts upon the face of the clock, and a circuit-controlling device for closing the circuit therethrough for a period of definite duration, substantially as described.
- 40 6. In a program-clock, the combination with the hour-hand b of said clock loosely mounted upon the shaft of the minute-hand and carrying a traveling contact b' , a ratchet-wheel b^2 rotating with the said hour-hand, pawl b^3 en- 45 gaging teeth upon the said ratchet-wheel, contacts a' mounted upon the face of the clock adapted to be adjustably disposed in the path of the traveling contact, a spring f , and a
- second driving-train, a time-keeping clock-train actuating the minute-hand, a stop g^5 50 normally checking the movement of said second driving-train adapted to be periodically actuated by the clock-train to release the second driving-train, and toothed wheel e mounted in said driving-train adapted to 55 periodically actuate the pawl b^3 to rotate the said ratchet-wheel and hour-hand a predeter- 60 mined distance and alter the circuit-connec- tions upon the clock-face, substantially as de- scribed.
7. The combination with the wheel k mounted to rotate with the minute-hand and carrying the pins $k' k'$, of the operating-lever h^2 mounted upon rocking shaft h , rocking shaft g^3 adapted to be rocked when said shaft h is 65 rocked, arm g^2 mounted upon shaft g^3 , notched disk g adapted to be engaged by said arm g^2 , arms $g^5 h^4$ carried upon shafts g^3 and h re- 70 spectively, wheel l' carrying the stop l , circuit- controlling disk c^3 and contact-spring c^2 , toothed wheel e , pawl b^3 operated thereby, hour-hand b , and ratchet-wheel b^2 mounted to 75 rotate therewith; substantially as described.
8. In a clock for transmitting electrical signals, the combination with the clock-train, of 75 a separate driving-train for the hour-hand of the clock, a stop normally checking the said driving-train of the hour-hand adapted to be periodically actuated by the clock-train to permit the driving-train to advance the hour- 80 hand a predetermined distance, a contact carried upon the hour-hand, contacts mounted upon the clock-face, each of which may be adjusted to be engaged by the said contact upon the hour-hand, and a circuit-controlling de- 85 vice provided in the driving-train of the hour-hand for completing the continuity of the circuit a definite length of time, substantially as described.

In witness whereof I hereunto subscribe my 90 name this 15th day of November, A. D. 1895.

ANDREW J. REAMS.
